(Cl. D34—15)

To all whom it may concern:

Be it known that I, Cecil F. Brown, a citizen of the United States, residing at Kansas City, in the county of Jackson and State of Missouri, have invented a new, original, and ornamental Design for a Hobbyhorse, of which the following is a specification, reference being had to the accompanying drawing, forming a part thereof.

Fig. 1 is a side elevational view of the hobbyhorse showing my new design.

Fig. 2 is a plan view thereof.

Fig. 3 is a front elevational view, and
Fig. 4 is a rear elevational view thereof.

I claim:

The ornamental design for a hobbyhorse, as shown.

CECIL F. BROWN.
